[57] CLAIM

The ornamental design for fruit clamshell container, as
shown and described.

DESCRIPTION

FIG. 1 is a perspective view of a fruit clamshell container showing my new design;

FIG. 2 is a top plan view thereof;

FIG. 3 is a side elevational view thereof;

FIG. 4 is a bottom plan view thereof;

FIG. 5 is a second side elevational view taken from a
position directly opposite that of FIG. 3; and,

FIG. 6 is another side elevational view from a position

90° in either direction from the view of FIG. 5.
